UNITED STATES PATENT OFFICE.

DAVID SCHOENTAG, OF GLASCO, AND ELMER J. LATUSS, OF ALBANY, NEW YORK.

LIQUID-HYDROCARBON DISTRIBUTER FOR ROADS.

1,028,288.

Specification of Letters Patent.

Patented June 4, 1912.

Application filed January 19, 1911. Serial No. 603,543.

To all whom it may concern:

Be it known that we, DAVID SCHOENTAG and ELMER J. LATUSS, citizens of the United States, and residents of Glasco, Ulster county, State of New York, and Albany, county of Albany, State of New York, respectively, have invented certain new and useful Improvements in Liquid-Hydrocarbon Distributors for Roads, of which the following is a specification.

This invention relates to a device for spreading liquid-asphalt over crushed stone beds in road building as well as for distributing oil on top of the finished road to bind the fine surface together.

One of the objects of the invention is the production of a simple, low-cost one-man device which may be used by unskilled labor during any part of the year.

20 A further object is to provide a discharge-chamber of improved construction disposed transversely immediately below the storage and supply-tank, by means of which improved distribution is effected, the path 25 affected extending at both sides beyond the supporting wheels, together with novel means for regulating the discharge from the discharge-chamber, either uniformly or differentially throughout the discharge 30 passage.

A further object is to provide means for causing the material entering the discharge-chamber to be distributed substantially uniformly throughout the length thereof.

35 A still further object is to provide the discharge-chamber with a vent conducting to the free and uniform flow of the fluid.

In the drawings hereto annexed Figure 1 is a plan view of the invention, with parts 40 broken away and in section; Fig. 2 is a vertically longitudinal sectional elevation, on line 2—2, of Fig. 1; Fig. 3 is a rear end view; Fig. 4 is a view of the front and underside of the discharge-chamber looking in the direction of the arrow 4 of Fig. 2; and Fig. 5 is a view of the same parts looking at right angles to Fig. 4.

The device comprises an oblong storage and supply-tank 10 supported by a pair of 50 wheels 11, which are mounted on the ends of a rod or axle 12 passing through a transverse tube 13, the latter being secured to the side walls of the tank and constituting in effect a brace therefor. The ends of the 55 said tube 13 extend beyond the tank and

form end thrust bearings for the hubs of the wheels 11, and the tube and rod afford a strong axle-support for the wheels as well as a brace for the tank while obviating any danger of leakage at this region. A pair 60 of shafts 14 secured to the tank and extending forwardly therefrom constitute means whereby the operator may draw the cart-like device. Beneath the rear end of the said tank 10 is a transverse discharge-chamber 15, the latter having its ends extended beyond the sides of the tank and beyond the outer lines of the wheels so that the latter need not travel on a previously oiled strip or path. The discharge-chamber 70 75 80 85 90 95 100 105 110

has a rear wall 16 which is preferably vertical and a front wall 17 which inclines downwardly and rearwardly toward the wall 16. The top of the said discharge-chamber may be formed by the bottom wall 75 of the tank 10. The lower and rear edge of the said wall 17 is spaced from the wall 16 so as to provide a transversely inclined slot-like discharge-opening 18 extending the full length of the discharge-chamber. The ends of the discharge-chamber 15 are formed flaring as shown in Figs. 1, 3 and 4, the triangular end walls 19 of the chamber being inclined downwardly and outwardly. The said discharge-chamber 15 communicates with the interior of the tank 10 by means of a valved-opening 20 disposed centrally or eccentrically with reference to the longitudinal axis of the device. This opening is shown as provided with an upwardly extending rim seat 20^a on which a vertical valve 21 normally rests, the stem of the valve being suitably guided in the upper and lower arms of a bracket 22 fixed to the interior of the said tank 10. A forwardly-extending lever 23 is pivotally connected at its rear end to the stem of the said valve 21 and fulcrumed intermediate its length on a pivot-pin 24 which is carried by an eyebolt 25; the latter passes through and is secured to the tube 13 and the rod 12 whereby the said rod is held against turning. A vertical operating rod 26 is pivoted at its lower end to the forward end of the said lever 23 and is provided with a forwardly-projecting handle 27 within convenient reach of the operator. The rod 26 has a catch 28 which is adapted to engage with a lip 29 formed from material removed from the top of the tank to afford the opening 110

through which the rod 26 operates. A tension spring 30 secured at its upper end to the top of the tank 10 and at its lower end to the forward part of the lever 23 holds the 5 valve 21 normally seated, the said catch 28 being engaged with the lip 29 to hold the valve open against the tension of the spring. A horizontally-elongated baffle-plate 31 is supported within the discharge-chamber 15 10 at a certain distance below the top thereof and directly beneath the opening 20, extending for a considerable portion of the length of the chamber so as to distribute the descending oil or asphalt to the end portions of the chamber as well as to the part 15 thereof more immediately below the opening. The said plate 31 is preferably as wide as or wider than the opening 20 and may be supported at its ends by bent-up lugs 32 20 secured to the top wall of the chamber.

As shown in Fig. 3 there may be a single valved-opening 20 for supplying the entire length of the discharge-chamber 15 with liquid. Fig. 1 illustrates how the 25 discharge-chamber may be divided by a transverse partition 33 into separate compartments, one of the compartments preferably being materially longer than the other, so that a considerable variation 30 in the width of the strips oiled can be secured by discharging the liquid from the longer compartment or from the shorter compartment or from both. In this case the smaller compartment is provided with 35 a similar valved-opening 20^b, the valve of which is operated in a similar manner by a rod with a handle 27^a through a lever 23^a, the two valves being independently operable. A gate 34, shown in the form of an 40 angled-plate is clamped to the front wall 17 of the discharge-chamber by means of wing-screws 35, which are secured to the side wall 17 and pass through transverse adjusting-slots 36 in the plate, in order that the plate 45 may be slid up and down and held at any point of adjustment, thereby enabling the width of the slot-like discharge-opening, and therefore the quantity of liquid discharged, to be quickly regulated at will. 50 Supplemental gates or plates 37, each materially shorter than the plate 34, enable the rate of discharge through different portions of the discharge-opening to be regulated independently. These supplementary gates 55 37 are shown as provided with slots 38 receiving the same bolts as the slots 36, so that the supplementary gates are adapted to slide back and forth to regulate the flow through the end portions of the discharge-opening. The angled-flanges 39 of these short plates 37 may be located at their upper ends so as to constitute stops for engagement with the upper edge of the main regulating-plate 34, the plates 37 being disposed 60 between the plate 34 and the wall 17. 65

In order to prevent obstruction or irregularity in the flow of the liquid into and from the discharge-chamber by the attempted passage of air upward through the valved-opening 20, a vent-pipe 40 is provided, the latter extends upwardly from one end of the discharge-chamber 15 outside of the tank 10 and terminates with its open upper end at a suitable elevation. 70

A fire-box 41 is removably located immediately below the tank 10, for the purpose of heating the oil in cold weather or when desirable. The said fire-box 41 is preferably constructed from a single sheet of metal in the form of a tray or shallow box consisting of a bottom, two sides and a rear end wall, the top of the box being formed by the bottom of the tank 10 and the front end of the box by a door 42 hinged at its upper edge to the front wall of the tank and preferably inclined downward and forward so as to remain closed by gravity, the front end of the fire-box being correspondingly beveled. The fire-box is hung low with its bottom at a short distance above the level 90 of the ground, so that it acts effectively to heat the top of the road as well as the contents of the tank. The fire-box is detachably supported by means of side hangers 43 which are removably secured at their upper ends to the sides of the tank by means of bolts and nuts 44, the bolts being received in horizontal slots 45 formed with the side edges of the hangers. The door 42 may be held open by means of a chain 46, the links 100 of which are adapted to engage with a hook 47 on the front of the tank. In order to prevent the fire-box from slipping forward, a lip 48 is bent down from the material of the bottom of the box at the rear end thereof 105 so as to engage with the edge of the rear hanger 43, the opening left by the removal of this material being closed by the horizontal portion of this hanger. A flue 49 extends upwardly from an opening in the 110 bottom of the tank 10 through an opening in the top thereof so as to receive a chimney section 50 at its upper end and to provide draft for the fire-box. 115

The top of the tank is provided with two hinged covers 51 and 52, provided with suitable handles, the latter being located in front of the chimney and affording access to the main portion of the tank and the former being in rear of the chimney and affording access for purposes of filling the tank. A strainer basket 53 is hung within the opening covered by the lid 51, to prevent the interior of the device being choked by solid or semi-solid matter. A baffle or 120 "wash" plate 54 disposed transversely within the tank intermediate the length thereof but not extending quite to the bottom prevents the liquid contents of the tank from 125 washing back and forth too violently. A 130

gage 55 is provided at one side and at the front of the device, preferably in alinement with one end of the discharge-chamber 15 so that the line connecting them is parallel 5 with the wheels. The said gage 55 is within convenient range of the eye of the operator drawing the device and enables him to tell at a glance whether he is drawing the apparatus so as to oil a strip the margin of which 10 touches or overlaps the strip previously oiled. The gage is shown in the form of a vertical rod 55 slidably held for vertical adjustment by means of a set-screw 57 in a bracket 56, the bracket being secured to one 15 of the shafts 14 as by means of a set-screw 58. A bib 59 at the forward end and bottom of the tank enables the latter to be drained. A stop 60 projecting below the edge of the rear wall 16 constitutes a guard 20 to prevent the discharge opening 18 and therewith connected parts from touching the ground.

The operation of the device will be readily apprehended. The tank is filled with 25 liquid asphalt or oil as the case may be, the operator takes his position between the shafts, opens one or more of the valves, and draws the device forward along the road thus coating a strip thereof with the liquid 30 contents discharged at the rear. He proceeds in like manner drawing the cart back and forth so as to coat successive strips until the oiling of the entire width of the road is completed. He can regulate the 35 rate of flow of the liquid from the device and also the horizontal width of the discharge, the latter ability enabling him to save material when oiling the last uncrossed strip of the road which may be materially 40 narrower than the maximum strip for which the device is adapted. When it is desired to heat the contents of the tank and the surface of the road, the operator attaches the fire-box beneath the tank and 45 places live brands therein, though the fuel may be ignited if desired after being placed in the box. The remainder of the operation has already been described.

Having described our invention, what we 50 desire to secure by Letters Patent and claim is:—

1. In a device of the character described, the combination of a wheeled tank for the reception of liquid asphalt or the like, a 55 straight transverse discharge chamber extending at its ends beyond the sides of the tank, said chamber being covered by the rear portion of the tank with its top directly against the bottom thereof and having 60 its front and back walls downwardly convergent, the lower edges of said front and back walls being spaced to afford a slot-like discharge opening extending the full length of the chamber, a gate slidably 65 over one of said walls transversely of the

discharge slot, valved connection between the top of the chamber and tank, and means at the front of the tank for controlling said valved connection.

2. In a device of the character described, 70 the combination of supporting wheels, a tank for the reception of liquid asphalt or oil carried between said wheels, draft means at the front of said tank, a straight transverse discharge chamber extending at 75 its ends beyond the sides of the tank and having valved connection with said tank, the upper and larger portion of said discharge chamber being disposed directly against the tank, said discharge chamber 80 having a rearwardly and downwardly inclined front wall, the lower edge of said front wall being obliquely spaced from the rear wall so as to afford a continuous discharge opening throughout its full length, 85 and means accessible from the front of the device for controlling said valved connection.

3. In a device of the character described, the combination of a wheeled tank for the 90 reception of liquid asphalt or oil, a discharge chamber of substantially triangular cross section with its base located immediately against the bottom of said tank adjacent the rear wall thereof and having 95 at its apex a continuous discharge opening arranged transversely of the device, a valved connection between said tank and said discharge chamber, a regulating gate disposed parallel to said discharge opening 100 and adapted to slide transversely of the same over its entire length, and a relatively short cut off gate also slidably transversely of said discharge opening and being adjustable independently of the regulating gate to vary the operative length of 105 the discharge opening.

4. In a device of the character described, the combination of a wheeled tank for the reception of liquid asphalt or oil, a discharge chamber having its top portion directly against the bottom of said tank and its rear wall adjacent the plane of the rear wall of said tank, a valved connection between said discharge chamber and said tank, 115 said discharge chamber having a transversely oblique slot-like discharge opening at its lower edge extending the entire length of the discharge chamber and arranged transversely of the device, an elongated regulating plate arranged parallel to and mounted to slide obliquely across said opening on the under side of the front wall of the discharge chamber adapted to adjust the operative width of said opening, and a relatively short plate mounted slidably between 120 said regulating plate and the underside of said discharge chamber adapted to cut off part of said opening.

5. In a device of the character described, 130

the combination of a wheeled tank for distributing liquid asphalt or oil, a discharge chamber directly connected to the tank in such manner that the bottom thereof forms 5 the top of said discharge chamber, said chamber comprising a vertical rear wall, an angularly disposed front wall and ends extending beyond the wheel tread at both sides and being provided with a slot-like opening 10 at its lowest edge, a gate for regulating the operative width of said slot-like opening, a valved connection between said discharge chamber and said tank, means for operating said valved connection accessible from the 15 front of said device and a baffle plate arranged below said valved connection for distributing the flow therefrom evenly throughout the slot.

6. In a device of the character described, 20 the combination of a wheeled tank for the distribution of liquid asphalt or oil, a prism-shaped discharge chamber directly attached against the bottom of said tank and being provided at its lower edge with a slot-like 25 opening in advance of the rear wall of the tank, a valve communicating between said tank and said chamber, said valve being located substantially above the slot-like opening, a valve stem, a guide bracket there- 30 for attached to the bottom and side wall of said tank, a brace between the side walls of said tank, a lever supported from said brace, one end of said lever being connected up with said valve stem, a rod at the other end 35 of said lever adapted for manual operation and means formed with said rod for holding said valve open or closed at will.

7. In a device of the character described

the combination of a wheeled tank for the reception of liquid asphalt, or oil, a transverse discharge chamber immediately below the rear part of said tank and within the limit thereof, projecting beyond the sides of the tank and outer lines of the wheels, the end walls of said chamber being inclined 40 downwardly and rearwardly, the lower edge of the front wall being spaced above and in front of the lower edge of the rear wall so as to afford a transversely inclined slot-like opening extending the full length of the 45 discharge chamber, and valved communicating means between said discharge chamber and said tank, said communicating means being directly over the discharge opening.

8. In a device of the character described, 50 the combination of a wheeled tank for distributing liquid asphalt or oil, a discharge chamber with a flaring top portion attached immediately to the under side of the tank and its bottom terminating in a sharp corner 55 and provided with a continuous slot along its entire bottom length, a valve of relatively large size between the tank and distributing chamber and a vent extending upwardly offset from the valve adapted to 60 free the discharge chamber from air entering the slot.

Signed at the borough of Manhattan in the county of New York, and State of New York this 18th day of January A. D. 1911. 70
